JAMES A. MURDOCK, OF TULSA, OKLAHOMA

DISPENSING TOP FOR BOTTLED CARBONATED LIQUIDS

Application filed May 2, 1927. Serial No. 188,211.

This invention relates to a dispensing top or head arranged to be detachably mounted over the closure caps of bottles of the type in which an exterior annular shoulder is presented and in which carbonated liquids are usually packaged.

It is well known that once the "charge" of a carbonated beverage is dissipated, its value as a refreshing beverage is lost. Where the entire contents of such bottles are not to be used at once, the potency of the beverage remaining will be retained by the use of my dispensing top. Frequently, at drink fountains, large bottles of carbonated beverages, such as gingerale, are used to fill individual orders, the contents of one bottle being gradually used up in this way, the same bottle being sometimes left unopened or only partly recapped over long periods and the beverage thereby becoming flat and unsalable.

It is the object of my present invention to provide a detachable dispensing top for such bottles in which is incorporated means for perforating the closure cap of the bottle to permit the contents to be discharged.

These and other features of the invention will be seen from the following detailed specification read in connection with the accompanying drawings forming part thereof and in which

Figure 1 is a vertical sectional view of my dispensing top applied to a bottle, the neck portion and cap of which is shown in section.

Figure 2 is a view in elevation of the right hand side of the dispensing top and bottle neck shown in Figure 1.

Figure 3 is a top plan view of the dispensing top shown in Figure 2.

Figure 4 is a top plan and

Figure 5 a fragmentary vertical section of the dispensing top showing a modified form of the attached shoulder engaging clamp.

Referring to the drawings by numerals, 1 indicates a bottle having the usual closure cap 2 crimped over the edge of its mouth, its downturned edge providing an annular shoulder 3.

The dispensing top of the present invention

is designed to be locked over the cap 2 and is in the form of a head having a base portion internally chambered annularly at 5 and having its base open and its edge provided with a chambered annular groove in which is seated a packing gasket 6 of compressible material designed to seat on the closure cap 2 and be held tightly locked thereon by the means hereinafter described.

The chambered base 4 as it uprises is tapered inwardly and continued upwardly to form a neck portion 7. At one side this neck portion is formed with an offset spout 8 communicating with the chambered base 4 by means of an inclined passage 9 which adjacent to its point of junction with the base chamber is turned to extend vertically and centrally of the head and base. The junction of the spout passage and the chambered base is provided with a raised portion or boss 70 forming a valve seat 10. The neck portion 7 extends centrally in line with the annular chamber 5 and is formed with a central pocket 11 therein from the lower end of which a tubular guide opening extends downwardly centrally through the vertical lower end of the passage 9 and through the annular chamber 5. A cap perforating plunger 13 having a flanged operating head 14 connected thereto is guided through said tubular guide opening 12, the shank of its head 14 being sized to fit within the pocketed portion 11 of the neck. A coiled spring 15 is seated within the pocket 11 with its lower end engaging an abutment washer 16 at the base of said pocket and encircles the plunger 13 and the shank of the operating head 14 with its upper end abutting the under side of the head. This spring normally acts to lift the operating head and its attached plunger to raise the cap perforating lower end of the plunger above the closure cap and to bring and hold the valve disk 17, seated on and carried by the plunger, firmly against the valve seat 10. It will be obvious that when the plunger head 14 is forced downwardly its point will perforate the cap 2 to permit the contents of the bottle to discharge. Release of the plunger head causes spring 15 to retract the plunger point bringing valve 17 against its seat to re-

tain the contents of the bottle within the same until it is desired to dispense them. This retaining action is increased by the pressure of the released carbonating gas acting against 5 the valve. The dispensing is effected by tilting the bottle and partially depressing the plunger head.

Obviously the dispensing cap is locked over the end of the bottle and I have accordingly 10 provided the base portion 4 with depending lugs 18 (Figures 3, 4 and 5) having hooked or offset lower ends to engage under the annular shoulder on the neck of the bottle, which, as shown in the drawings, is provided 15 by the edge of the closure cap. At the opposite side of the base 4 spaced niches 19 are formed with inwardly extending apertures in which are seated the inwardly bent hinging ends 20 of a wire bail which may be 20 of any suitable construction providing means movable to engage under shoulder 3 and in conjunction with lugs 18 detachable to lock the dispensing head on the closure cap. The wire bail form shown in Figures 1 to 3 of 25 the drawings and having the hinging ends 20 heretofore referred to, is provided with the curved spring loop 21 formed from and positioned between the hinged arms 20 and having a horizontal shoulder engaging end 30 22. When the lugs 18 are positioned under the annular shoulder 3 at one side of the bottle, the dispensing head is pressed down on the cap 2 and the bail is swung downwardly, the locking bar 22 of its spring loop being 35 sprung under the annular shoulder 3 and held there by the tension of its spring arms 21.

In the modified form of locking bail shown in Figures 4 and 5, the base portion 4 at the side opposite to the lugs 18 is enlarged laterally and vertically to provide opposite flat faces 23 to which are hinged the spaced upper ends of the bifurcated arms 24 of a clamping lever, the lower end 25 of which is formed as a finger grip. The enlargement 40 of the base portion 4 at this side of the bottle brings said base portion downwardly to enclose and reach to the lower edge of the closure cap 2. A flat spring 26 has its lower end seated in the handle portion 25 and its 45 upper portion curved and formed to enter beneath and engage the shoulder 3 and to be tensioned into locked engagement therewith when the clamping lever is swung downwardly as shown in Figure 5.

55 I claim:

1. A dispensing top for bottles of the type having a closure cap and presenting an exterior annular shoulder comprising an internally chambered head having a discharge 60 opening to the exterior, clamping means carried by said head to engage said annular shoulder detachably to lock the said head on the bottle, and means carried by said head and operable to perforate the closure cap to 65 permit the bottle contents to discharge.

2. A dispensing top for bottles of the type having a closure cap and presenting an exterior annular shoulder, comprising a cap covering head having a liquid discharge opening therein, and a communicating chambered base portion arranged to seat over said closure cap, clamping means carried by said head to engage said annular shoulder detachably to lock the said head on the bottle, and means carried by said head and operable to 70 perforate the closure cap to permit the bottle contents to discharge. 75

3. A dispensing top for bottles of the type having a closure cap and presenting an exterior annular shoulder comprising a cap covering head having a valved upper liquid discharge opening therein and a communicating chambered lower base portion arranged to seat over said closure cap, clamping means carried by said head arranged to engage said annular shoulder detachably to lock the said head on the bottle, and cap perforating means carried by said head operable to 80 perforate the cap to permit the bottle contents to discharge. 85

4. A dispensing top for bottles of the type having a closure cap and presenting an exterior annular shoulder comprising an internally chambered head having a discharge opening to the exterior and provided with an integrally formed lug arranged to engage under said annular shoulder at one side and with cooperating movable clamping means to engage under said shoulder at the opposite side detachably to lock said head on the bottle cap, means carried by said head and movable to and from a position to perforate said cap to permit discharge of the bottle contents. 90

5. A dispensing top for bottles of the type having a closure cap and presenting an exterior annular shoulder comprising a cap covering head having a chambered base arranged to seat over the closure cap and a communicating discharge passage extending therefrom at an angle, cap puncturing means carried by and within said head for movement in a direction lengthwise of a bottle, and means carried by said head arranged to engage said annular shoulder detachably to clamp said head over the bottle closure cap. 105

6. A dispensing top for bottles of the type having a closure cap and presenting an exterior annular shoulder comprising a cap covering head having a chambered base portion arranged to seat over the closure cap and a communicating discharge passage extending therefrom, shoulder engaging means carried by said base portion arranged to engage and detachably to lock said head on the bottle cap, and means carried by said head and constructed and arranged for movement through said chambered base to puncture the 110 115 120 125 130

bottle closure cap to permit discharge of the contents through the perforation so made.

7. A dispensing top for bottles of the type having a closure cap and presenting an exterior annular shoulder comprising an internally chambered head having a discharge opening to the exterior and a communicating chambered base portion arranged to seat over the bottle closure cap, a fixed shoulder-engaging lug depending from one side of said base, a movable shoulder-engaging member at the opposite side cooperating therewith detachably to lock said head on the bottle cap, and a cap perforating plunger mounted in said head for movement through its chambered portion to perforate said cap.

8. A dispensing top for bottles of the type having a closure cap and presenting an exterior annular shoulder comprising a cap covering head having a chambered base portion arranged to seat over said closure cap and a discharge passage forming therewith a valve seat and extending therefrom at an angle, a cap perforating plunger mounted in said head for movement longitudinally of the bottle and extending through said valve seat, a valve carried by said plunger and cooperating with said seat, and means carried by the head and cooperating with said annular shoulder detachably to lock the head on the bottle closure cap.

9. A device of the character described comprising a body applicable to the closure end of a container and having a discharge opening, and means carried by said body for initially perforating said closure and thereafter to control the flow of the contents of said container through said perforated closure.

10. A device of the character described comprising a hollow body adapted to be attached in sealing contact over the closure end of a container and having a discharge opening, and a combined closure perforating and valve member mounted in said body.

45 11. A device of the character described comprising a body member adapted to be clamped over the closure end of a container and provided with a discharge opening, a stem movably mounted in said body and carrying a closure perforating member at its end, and a valve member mounted on said stem and operative thereby after said closure is perforated to control the discharge of the contents of said container through said discharge opening.

12. A dispensing cap for bottles comprising a body member adapted to be fixed in sealing contact about the sealed mouth of a bottle and provided with a discharge opening, a stem extending through said body and movable endwise to puncture the sealing closure of said bottle, a spring acting on said stem to retract the same from the opening punctured thereby, and a valve member on said stem co-acting with a seat intermediate the interior of

said bottle and said discharge opening to control the dispensing of the contents of said bottle.

13. A dispensing cap for bottles comprising a body member adapted to be fixed in sealing contact about the sealed mouth of a bottle and provided with a discharge opening, a stem extending through said body and movable endwise to puncture the sealing closure of said bottle, a spring acting on said stem to retract the same from the opening punctured thereby, said body having a valve seal concentric with said stem, and a valve member mounted on said stem and coacting with said valve seat to control the flow of the contents of said bottle through said discharge opening subsequent to the puncturing of its seal.

14. A device of the character described comprising a hollow body member adapted to be applied in sealing contact around the sealed opening of a container and having a discharge opening, an endwise movable stem mounted in said body and provided with a closure puncturing member at one end normally held in retracted position, and a valve located between the interior of said container and said discharge opening including a valve member carried on said stem, said valve being opened and closed in the movement of said stem into and out of closure puncturing position.
